UNITED STATES PATENT OFFICE.

CHARLES J. DIEGES, OF NEW YORK, N. Y.

DESIGN FOR A CARD-CASE.

46,926.

Specification for Design.

Patented Feb. 9, 1915.

Application filed November 2, 1914. Serial No. 869,989. Term of patent 7 years.

To all whom it may concern:

Be it known that I, CHARLES J. DIEGES, a citizen of the United States, residing in the borough of Manhattan, city, county, and State of New York, have invented a new, original, and ornamental Design for a Card-Case, of which the following is a specification, reference being had to the accompanying drawing.

The figure is a front elevation upon an enlarged scale, showing my new design for a card case.

I claim:

The ornamental design for a card case, as shown.

CHARLES J. DIEGES.
